MILL FOR GRINDING LIQUIDS OR POWDERS

Sidney Richard Nelson Smith, Haglands, West
Chiltington, near Pulborough, EnglandApplication November 25, 1938, Serial No. 242,395
In Great Britain November 30, 1937

1 Claim. (Cl. 83—45)

This invention refers to improvements in and relating to mills for grinding liquids or powders.

It is an object of the present invention to produce a mill having a minimum number of parts.

5 It is a further object of the present invention to produce a mill in which the parts can be easily and quickly changed when necessary.

Other objects of the invention will be apparent from the detailed description with reference 10 to the accompanying drawing, in which:

Figure 1 is a longitudinal elevation partly in section of a mill constructed in accordance with this invention; and

Figure 2 is an enlarged sectional elevation of part of the mill.

15 Referring to the drawing, a horizontally closed cylinder 1 rigidly supported in a frame 9 is provided with an inlet port 5 and outlet port 5¹. A shaft 2 mounted centrally in the cylinder 1 is supported in bearings in the end cover plates of the cylinder 1 and uprights of the frame 9, one end of the shaft 2 projects outwardly and is provided with fast and loose pulleys 6 for connection in the usual way with a source of power for rotating the shaft 2.

20 Approximately mid-way of the length of the cylinder 1, the shaft 2 is apertured to accommodate a transverse arm 3. The shoes 4, 4, are each provided with a stepped aperture 4¹ and a collar 8. The ends of the transverse arm 3 are reduced, as at 3¹, and the reduced ends 3¹ fit into the stepped apertures 4¹ in the shoes 4 and are surrounded by the collars 8. Between the collars 8 and the reduced ends 3¹ of the transverse arm 3 are coiled springs 7, 7, one end of each abutting 25 against the step on the end of the arm 3, and

the opposite end abutting against the stepped aperture 4¹ of the shoe 4. Thus the shoes 4, 4 are continually pressed against the inner surface of the cylinder 1 by the springs 7, 7, ensuring efficient grinding of the material as the shaft is rotated.

It will be obvious that the shaft may be stationary and the cylinder may be rotated; or the shaft may be rotated and the cylinder may also be rotated, but in this case the cylinder will be rotated oppositely to the direction of rotation of the shaft.

I claim:

A mill for grinding liquids or powders comprising a horizontally arranged closed cylinder 15 provided with inlet and discharge ports, a shaft with a central transverse aperture mounted in bearings in the end plates of said cylinder, the cylinder and shaft being relatively rotatable, an arm with reduced ends extending substantially 20 across the cylinder passing through said central transverse aperture provided in the shaft and fixed thereto, a helical spring mounted over each reduced end on said arm, a grinding member, extending substantially the whole length of the cylinder, formed with a collar on the inner face 25 loosely mounted over each reduced end of said arm and spring and the outer face of the grinding member being of a corresponding curvature to the inner surface of said cylinder, the arrangement being such that the tension of the springs 30 will exert pressure upon the grinding members thereby forcing them into close contact with the inner surface of the cylinder.

SIDNEY RICHARD NELSON SMITH.
